UNITED STATES PATENT OFFICE.

AUGUST D. MEISELBACH, OF CHICAGO, ILLINOIS, ASSIGNOR TO MARGARET MEISELBACH, OF CHICAGO, ILLINOIS.

METHOD AND MEANS FOR BUILDING AND TESTING TUBULAR FRAMES.

Application filed April 28, 1920. Serial No. 376,561.

To all whom it may concern:

Be it known that I, AUGUST D. MEISELBACH, a citizen of the United States, and resident of Chicago, in the county of Cook and State of Illinois, have invented certain new and useful Improvements in Methods and Means for Building and Testing Tubular Frames, of which the following is a specification.

10 My invention relates to improvements in methods and means for building tubular frames, such as frames for bicycles and the like.

Such frames are usually built up of tubular or hollow connections and pieces of tubing, the tubing fitting and joined to the connections and secured thereto by brazing or otherwise. They usually consist of a number of pieces of tubing either straight 15 or curved and arranged at various angles. The practice heretofore has been to arrange the tubes and connections in their desired relations and by means of pins or the like hold the tubes and connections together 20 while the joints were brazed. It has been common practice to make different sections of the frame at different times and then assemble the several sections together and join them as described above. As my invention has so far been developed for the 25 practical purpose of reducing the cost and increasing the accuracy of results in the building of bicycle frames, I shall describe my invention in reference thereto, but it 30 should be understood that my invention is not thus limited.

A bicycle frame when completed, should be exactly symmetrical upon the two sides of a central vertical longitudinal plane, or 40 the finished bicycle will not be true or hold the several parts; viz., the wheels, et cetera in proper alignment or relative positions.

For instance the center line of the head connection should be in the plane with the 45 center line of the middle post, the upper and lower bars of the front part of the frame should be accurately in the same plane and the rear part should lie symmetrically on the two sides of the longitudinal 50 center plane and the rear adjusting slots for the rear wheel should be accurately parallel in position and at equal distances from the center plane.

In the common process of making frames 55 the parts are made up of the proper dimen-

sions and assembled and secured as already described, the frame and its parts being inspected at the several steps as to alignment and symmetry, but no assurance is had that the final results will be accurate in the 60 symmetrical frame desired. This is but illustrative of the necessity which now exists of bending, springing or otherwise adjusting the several parts to cause them to lie approximately in their true positions. 65 All of these various steps require the employment of highly skilled labor, but even so, the results are not satisfactory.

The bending and adjusting of the frame produces more or less noticeable depressions, kinks or bends and it is usually necessary to fill these depressions with solder, necessitating, in a factory building two hundred frames a day at least three men to do the soldering. All of this work and 70 expense is the result of imperfect work and does not add anything of real merit to the result and should not be necessary.

Furthermore when it comes to assembling the frame with wheels, et cetera, it 75 is necessary again to bend and space the various forks to cause the wheels to stand true therein, all of which detracts from the appearance of the machine and adds greatly to the cost.

By means of my invention unskilled labor can produce a larger number of frames in a day, and these frames will be accurate as to alignment and symmetry and the various joints will be perfect, in that their abutting 80 ends will be in accurate abutment not leaving open cracks of various sizes to be filled with solder, or other suitable filling material.

My invention resides in a method of arranging the several connections and frame parts or sections in assembled relation, clamping them tightly together in accurate alignment and symmetry and while thus clamped rigidly securing them together by 100 some metalizing process as by spot welding, either electric or acetylene.

The frame thus having all of its parts rigidly joined, its several joints are completed preferably by being dipped into 105 melted brazing material. The frame is then finished by having all of the parts cleaned of all superfluous metal, the several openings are accurately machined and then it is placed in a testing machine, which may 110

be the same as the one first used for aligning the parts or may be a similar machine especially arranged for testing. The crank case is rigidly clamped in its true position and the seat post tube is tested for accuracy as to its position relative to the longitudinal central plane of the frame. If it does not lie accurately in this plane it is sprung to one side or the other until it does. In building frames in accordance with my present invention, I find that the seat post tube usually lies within at least one-sixteenth of an inch of its true position. After adjusting the seat post tube accurately, a dowel pin is placed therein to hold it in its true position while the head connection is tested and adjusted. The head connection is tested by a shaft or mandrel held centrally in the head connection on collars which fit the end of the head which have been machined for the ball bearing cups. This shaft projects above and below the head and I provide slotted members for engagement with the shaft, said members having their center lines arranged in said longitudinal central plane and being movable horizontally therein from and toward the shaft. The slotted ends of these members are adapted to receive the shaft and when the head lies in its true position the slotted members can be moved toward the shaft and the shaft will slide freely into the slots therein.

When the U-shaped testing members can be placed upon the projecting ends of the shaft freely, the head then lies accurately in said central longitudinal plane.

The next step is to test the rear forks. I provide a horizontal test mandrel or shaft having shoulders properly spaced and having its longitudinal center in the said central longitudinal plane and movable, as a whole, back and forth relatively to the rear forks. This member is provided with bosses on its end fitting easily into the slots of the rear forks and when the member slides easily into both the rear forks and the inner sides of the forks lie snugly against the adjacent faces of the end collars or shoulders the forks are true with the balance of the frame.

A full and complete understanding of my invention will be attained from the following description taken in conjunction with the accompanying drawing forming part of this specification and in which I have illustrated a machine which I have found best adapted for the practice of my invention.

In said drawings, Figure 1 is a side elevation of a machine especially adapted for clamping the several parts of a bicycle frame in their proper related positions and then holding them rigidly in said positions while the several joints are spot-welded, a bicycle frame being shown as held in clamped position;

Figure 2 is a top plan view of said machine and bicycle frame;

Figure 3 is a fragmentary vertical section on the line 3-3 of Figure 2;

Figure 4 is a fragmentary horizontal section on the line 4-4 of Figure 1;

Figure 5 is a fragmentary substantially horizontal section on the line 5-5 of Figure 3;

Figure 6 is a fragmentary substantially horizontal section on the line 6-6 of Figure 1;

Figure 7 is a fragmentary vertical section of the seat post connection portion on the line 7-7 of Figure 2;

Figure 8 is a fragmentary vertical section of the connection at the lower end of the seat post tube;

Figure 9 is a fragmentary side elevation of the rear part of the bicycle frame and the adjusting head;

Figure 10 is an enlarged fragmentary side elevation of the rear fork and the adjusting head;

Figure 11 is a fragmentary plan view of the rear fork and the adjusting head;

Figure 12 is a fragmentary vertical section substantially on the line 12-12 of Figure 9;

Figure 13 is a side elevation of a machine especially adapted for testing and adjusting the bicycle frame after the several joints have been finished, a bicycle frame being shown as fitting properly in said machine;

Figure 14 is a plan view of the machine and frame shown in Figure 13; and

Figure 15 is a fragmentary side elevation of the forward part of the finishing machine and a bicycle frame, the frame shown partly in section.

In said drawings, 1 represents a machine in which the several parts of a bicycle frame are adapted to be positioned, aligned, clamped and held until the several parts have been secured rigidly together as by spot-welding or the like.

This machine comprises an elongated base 2 upon which the several parts are mounted. At the central portion of the base 2 is arranged two oppositely positioned standards 3 and 4. The standard 3 is relatively low and carries a transversely adjustable shaft 5 in a threaded bearing 6. The inner end of the shaft carries a doweling head 7 adapted to fit within one end of the crank case connection 8 of a bicycle frame. The outer end of the shaft 5 carries a hand wheel 9 by which the head 7 can be forced into to clamp a crank case or withdrawn to free it.

The opposite standard 4 is considerably higher than the standard 3 and is high enough to rise above the seat post connection 10 of a bicycle frame 11 placed in the machine. Projecting from the base of the

- standard 4 is a doweling head 12 similar on its free end and disposed opposite to the head 7 and in axial alignment therewith. This head 12 is preferably fixed and its shoulder 13 which contacts with the opposed end of the crank case 8 is arranged exactly one-half the length of the crank case from the central longitudinal plane of the machine so that when the crank case is clamped 10 between the shoulder 13 on the head 12 and the corresponding shoulder 14 on the head 7 the crank case will be positioned with its transverse central plane in the longitudinal plane of the machine.
- 15 The upper end of the standard 4 has secured thereto a projection 15 provided with a vertical threaded opening 16 in which a threaded shaft 17 is mounted and which is adapted to be moved up and down 20 by a hand wheel 18 on its upper end. The center line of the shaft 17 lies in the longitudinal central plane of the machine and said center line extended will cross the center line of the crank case at the transverse 25 center point thereof as both lie in the longitudinal central plane of the machine.
- The lower end of the shaft 17 is provided with a shoulder 19 adapted to contact with the upper face of the seat post connection 10 of the bicycle frame and it is provided with 30 a central doweling projection 21 fitting within the seat post connection and adapted to center and to hold this point of the bicycle frame truly in the longitudinal central plane 35 of the machine.
- The crank case connection 8 is provided with a transverse central nozzle 22 in its upper side adapted to receive and position what is known as a fishtail bushing 23 40 adapted to project through and beyond the nozzle 22 and to receive the lower end of the seat post tube 24 and accurately dowel and hold it on the crank case connection 8. The outer diameter of the nozzle 22 and 45 the seat post tube 24 are substantially the same and when the seat post tube is placed upon the fishtail dowel 23 and it is forced against the crank case connection its lower end contacts with the outer end of the nozzle 22.
- To connect the seat post tube 24 with the seat post connection 10 it is usual to provide a tubular bushing 25 for placement with the connection 10 which has an internal diameter suitable for the seat post of the bicycle. The lower end of this tubular bushing 25 receives, centers and dowels the upper end of the seat post tube 24.
- The seat post connection 10 is provided 55 with a central nozzle 10' on its lower side in which the tubular bushing 25 fits and against the outer end of which the upper end of the seat post tube 24 is adapted to contact. In using the machine for aligning the parts of 60 the bicycle frame the several parts may be
- loosely strung together and, as so far described, the operation of aligning the parts is as follows:
- The crank case is loosely supported on the heads 7 and 12. Then the frame is positioned 76 so that the dowel 21 on the shaft 17 can be entered into the open top of the seat post connection. Then the crank case is clamped tightly between the heads 7 and 12 thus accurately centering the crank case 75 and afterward the shaft 17 is screwed down to force the end of the seat post tube 24 into tight contact at each end with the adjacent shoulders. The pressure on the seat post tube is longitudinal thereof and sufficient pressure can be applied to tightly close the joints between the ends of the tube and the adjacent shoulders so that there are substantially no cracks left at these points to be filled with solder after the joints have 80 been brazed.
- Besides the crank case, the seat post connection and the vertical seat post tube 24 the bicycle frame consists of a head connection 26, an upper tubular bar 27 connecting the upper end of the head with the seat post connection, a lower tubular bar 28 connecting the lower part of the connection with the crank case, which together constitutes the forward part of the frame and 90 a rear part or section of the frame. The rear part of a bicycle frame consists of two side frames each comprising an upper tubular bar 29 and the lower tubular bar 30. These bars are connected together at their 100 rear ends by the rear wheel slotted plate 31. The forward end of the tubular bar 29 is joined to the seat post connection and the forward end of the lower bar 30 is joined to the crank case 8.
- Furthermore the two side frames are 105 brazed and joined together by a short tubular brace 32 which acts as a spacer between the two upper members 29 and a similar tubular brace 33 which serves as a spacer for the two lower members 30. These spacers are arranged a suitable distance from the center of the rear wheel of the bicycle to serve as supports for the rear mud guard and as usually arranged they are placed 110 just beyond the periphery of the rear wheel.
- My method includes the centering of these braces and consequently the members 29 and 30 as well as the various extremities of the 115 several parts of the bicycle frame.
- For centering and aligning the head connection 26 and forcing the tubular bars 27 and 28 to tight shoulder fits at their ends I provide a standard 34 rising from the forward end of the base 2 and carrying two vertically spaced horizontally extending members 35 and 36.
- The upper member 35 is provided with a substantially vertical opening 37 and the lower member 36 is provided with a simi- 120 125 130

4

lar opening 38. These openings are in axial alignment and in inclined relation to the vertical at the same angle as the head connection 26 is inclined to the vertical when 5 the seat post tube 24 is set vertical, as in the machine, that is with the upper end farther from the seat post tube than the lower end. The opening 37 in the upper member 35 is larger than the lower opening 38 to receive 10 a clamping cam shaft 39. The lower end 40 of the shaft 39 fits the smaller opening 38 and the upper end 41 fits in the larger opening 37. The middle portion 42 of the shaft is formed eccentric to the axial center line of 15 the shaft as best shown in Figures 1 and 5 and is adapted to force the head connection 26 rearwardly toward the seat post tube when the shaft is rotated to the position shown in Figure 3, where its cam extends 20 from the rear side of the shaft.

The head 26 is provided with two rearwardly extending nozzles 43 and 44 to be connected respectively to the upper frame bar 27 and the lower frame bar 28. These 25 nozzles are of the same external diameter as the bars 27 and 28 and to strengthen the joints between the head and the bars, each nozzle is provided with a fishtail bushing 45 similar to the bushing 23 used in joining 30 the seat post tube 24 to the crank case 8.

Each of the bushings 45 is provided with flanges or partial flanges 46 on their inner ends which are adapted to lie in contact with the inner surface of the cylindrical portion 35 of the head 26 and to be brazed thereto when the joint is finished. These fishtail bushings are entered into the nozzles 43 and 44 and then the partial flanges or projections are spread out and formed to conform 40 with the inner surface of the head 26. The outer ends of the nozzles 43 and 44 are trued up, and as the sheet metal of which the head 26 is made is thicker than the walls of the tubes 27 and 28, the truing of the 45 nozzles leaves thin circumferential doweling flanges 47 on the outer ends of the nozzles 43 and 44 which accurately fit within the tubes 27 and 28 centering them accurately and providing joints between the 50 ends of the tubes 27 and 28 and the nozzles which will be close and free of unsightly cracks which have to be filled with solder after the brazing operation.

The rear end of the upper tubular bar 27 55 is received upon and centered by the nozzle 48 formed on the seat post connection and the rear end of the lower tubular bar 28 is received and centered by one of the fishtail bushings 45 carried in a suitable central nozzle 49 and formed out of the wall 60 of the crank case 8.

Usually the bicycle frame is brought to the machine with the several parts assembled and loosely held in assembled condition, and after the securing of the ver-

tical bar 24 in place as described the shaft 39 is inserted through the openings 37 and 38 and through the head 26 with the projecting side of the middle or cam portion 42 of the shaft projecting toward the standard 70 34. Then by rotating the shaft the cam portion is turned toward the rear and is forced against the flanges 46, forcing them into close contact with the inner wall of the head 26 and forcing the head, as a whole, toward the seat post tube 24. In this clamping process the tubes 27 and 28 are clamped endwise tightly between the shoulders on the several connections and the bushings 45 in the head connection are forced tightly into 75 position. To hold the several fishtail bushings 45 in the crank case 8 against being pushed into the connection during the operation of forcing the several tubes into tight contact with said connection I preferably 80 insert a cylindrical plug 50 which fits tightly enough within the hollow crank case to prevent the inward movement of the several bushings.

To hold the head connection from being 90 forced sidewise out of the true vertical central longitudinal plane of the machine when the eccentric shaft 37 is rotated to force the head and bushings rearwardly I provide a slotted guide member 51 having 95 a slot 52 fitting the sides of the head connection 26 and mounted on the standard 34 for movement back and forth.

The slot extends exactly vertical and central as related to the central vertical plane 100 of the machine so that as the eccentric portion 42 of the shaft 37 is rotated to clamp the frame parts the head 26 is held against sidewise movement out of its true central position.

It should be understood that the function 105 of the eccentric or cam shaft 37 will be effective if the rear ends of tubular bars 27 and 28 are held stationary properly spaced whether by being entered upon the dowels 110 upon the two connections or otherwise, at least so far as the production of the tight joints between the head connection and the tubular bars is concerned. In other words the method which I have devised of clamping the head upon the upper and lower bars is new and useful in and of itself whether combined with the added function of setting the rear ends of the tubular bars on the other connections or not.

Having properly clamped the head connection and the upper and lower bars as described upon the seat post connection, and the crank case connection the next step 115 is to position and clamp the rear parts of the frame.

The rear side frames which each consists of an upper bar 29, a lower bar 30, and a rear wheel slotted connection 31 are first 120 assembled. The connection 31 is usually 125

made of flat steel about one-eighth of an inch thick having forwardly extending projections 53 and 54, and the rear ends of the tubes 29 and 30 are flattened down to substantially fit these flat projections.

To temporarily hold these tubes on the projections the projections are provided with perforations 55 and the rear inner wall of each tube is forced into this opening as shown at 56, Figure 11, by means of a suitable round ended punch. The side frames are brought to the machine thus assembled and the forward end of the upper tube 29 is placed upon a suitable doweling projection 57 formed upon the seat post connection 10. The seat post connection is provided with two of these projections 57 one for each of the upper tubes 29 and slightly spread apart so that they can be drawn together to properly clamp a seat post which fits within the seat post bushing 25. The bushing 25 has a longitudinal slit or cut 58 connecting with the space between the lugs or the projections 57 so that it can be compressed upon the seat post. The forward ends of the bars 29 are thus brought close together while the rear ends are spaced apart in position to receive the rear axle of the rear wheel between them. The forward ends of the lower bars 30 are received and properly fixed upon suitable dowels 59 on the crank case 8. These dowels 59 are formed of the fishtail bushings 45 which are mounted within suitable hollow bosses or projections 60 projecting from the crank case, and spaced the same distance laterally from the longitudinal central plane of the frame.

To properly space and set the rear ends of the rear side frames, that is the rear wheel slotted plates 31, I provide a transverse shaft 61 having fixed collars 62 at its ends, the outer faces of said collars forming shoulders which are spaced apart the same as and simulate the fixed collars or bearings at the ends of the rear wheel hub and carried on the rear axle. Upon these shoulders are diametrically arranged projections 63 shown by section lining in Figure 10, which substantially fill the slots 64 for the rear axle in the connections 31. Centrally upon the projections 63 I provide the shaft member 61, threaded projections 65 extending axially of the shaft 61, for receiving clamping nuts 66 by which the plates 31 can be tightly clamped against the collars 62. When so clamped the plates 31 are arranged with their slots 64 exactly parallel with each other. I mount the member 61 in a horizontal position in a bore 67 provided in a block 68 which in turn is mounted in a vertical opening 69 provided in a longitudinally movable head member 70.

This head 70 is carried on a shaft 71 ar-

ranged longitudinally of the machine and extending horizontally and is held against transverse movement in true vertical position by projections or flanges 72 which engage the parallel sides 73 of a guide member 74 mounted on the base 1 of the machine at 70 the rear end thereof.

The guide member 73 is provided with a standard 75 at its forward end and a similar standard 76 at its rear end and in which the shaft 71 is rotatably mounted. 75 The shaft is screw threaded between said standards and the head is provided with a threaded opening for receiving the same. The shaft is held against longitudinal movement by a collar 77 which bears against the rear end of the standard 76 and a similar collar 78 which bears against the forward side of the standard 75. The shaft is provided with a hand wheel 79 on its rear end by which it can be rotated to move the head 80 70 and the member 61 back and forth. The member 61 is arranged and held with the outer surfaces of the two collars 62 the same distance from the vertical central longitudinal plane of the machine so that when the 90 plates 31 are clamped upon same they are spread equally from the central plane of the machine.

In assembling a frame the slotted plates 31 are clamped upon the ends of the member 95 61 against the outer surfaces of the collars 62 by the nuts 66. The forward ends of the bars 29 and 30 are then entered upon their respective doweling projections and the head with the member 61 is pushed forward by the screw shaft 71 until the several ends of the tubes are pressed firmly into contact with the opposing shoulders on the connections 8 and 10.

One important feature of my method and 105 machine resides in the accuracy of the spacing of the rear slotted plates 31 for the rear wheel from the center of the crank case 8 which, of course, determines the spacing of the crank shaft and the axle of the rear wheel. This feature is important as the amount of adjustment of the rear axle in the slotted plates for the wear of the chain is limited and must be so arranged that the removal or addition of one link in the usual 110 one-inch pitch chain, now commonly used, will cause an adjustment of the rear shaft within the available adjustment provided by the slotted plates. In other words having decided on the chain to be used and the 120 dimensions of the bicycle frame, the crank case should be properly positioned relatively to the rear plates 31.

This proper distance having been once determined the machine is adapted to secure 125 such spacing. This is accomplished by providing a projection 80 on the forward end of the head 70 which is adapted to contact

with a similar projection 81 on the rear face on the standard 76 when the parts are properly positioned.

The head 68 is vertically movable in the head 70 fitting between parallel vertical walls 82. This is for the purpose of permitting the rear ends of the shaft to adjust themselves slightly vertically so that both the lower rods 30 and the upper rods 29 shall be properly clamped tightly endwise between the limiting shoulders.

In using the machine, having set in the side frames as described it is only necessary for the workman to turn the hand wheel 79 and force the head 70 as far forward as it will go, that is with the projections 80 and 81 in contact. At this time all of the side bars 29 and 30 should be tightly bound between the centering shoulders. If they are not thus bound then there has been a mistake made in preparing some of the parts.

As the side bars 29 and 30 of the rear frame are curved and inclined laterally their rear ends being spread farther apart than their forward ends, it is necessary to properly position and space these bars and hold them in such spaced relation relatively to the rim of the rear wheel. For the spacing of these bars I provide U-shaped strut members 83 and 84 which simulate somewhat the shape of the upper and lower parts of the rear frames. The member 83 is adapted to lie within the side bars 29 which form the upper rear fork and the member 84 is adapted to lie between the side bars 30 of the lower part of the rear frame. Each of these members is pivotally mounted on the forward part of the head 70 on suitable bolts 85 and 86 respectively. These members are somewhat shorter than the space between the side bars and each is provided with a forward central doweling projection 87 on the upper member and 88 on the lower member. The forward portions 89 and 90 of these members fit tightly between the bars 29 and 30 respectively at substantially the point where the rim and tire of the rear wheel will be positioned, so that when the frame is properly clamped in the machine these forward ends of the U-shaped strut members 83 and 84 properly space the side bars of the rear part of the bicycle frame apart.

To permanently hold the side bars 29 and 30 I provide tubular braces or supports 32 for the upper fork and 33 for the lower fork. The brace 32 is received between the two bars 29 at the point where they are bent in to draw them together to correspond with the projections on the seat post connection upon which they are doweled and similarly the brace 33 is placed between the forward end of the bars 30 where they are inclined inwardly to fit upon the dowels on

the crank case 8. The tubular strut 32 is provided with a central opening 93 to receive a small doweling projection 94 on the projection 87 carried by the U-shaped member 83 and similarly the strut 33 is provided with a small central hole 95 to receive a small projection 96 on the projection 88 carried by the U-shaped member 84.

In assembling the frame on the machine the tubular strut braces 32 and 33 are placed upon their doweling projections and as the rear forks are placed in position upon the machine the members 83 and 84 are aligned with their respective forks and the tubular braces are placed in position between the side bars of their respective forks, and as the head 70 is forced forward to clamp the bars 29 and 30 the tubular braces 32 and 33 are forced tightly between the side bars of the rear forks. The doweling openings 93 and 94 in said tubular braces being centrally arranged and the projections upon which they are mounted being centrally arranged relatively to the machine, the centering of the side bars of the rear fork is assured.

Having tightly clamped the several members of the frame in the machine, they are all held in such tightly clamped position until the several tubes and the several connections are permanently joined together by spot welding or by other suitable means. Preferably they are joined by means of an oxyacetylene welding torch the welding particularly joining the ends of the tubes to the head connection 26, the seat post connection 10, the crank case connection 8, and the rear fork connection 31, as indicated on the several drawings by the weld spots 96.

Besides the welding of the parts together to hold them rigid until the various joints are brazed or otherwise completed the heating of the parts in the welding process has an important function in the production of perfect work. This function is the relief of the strains incident to forcing the several parts into their desired positions.

It sometimes occurs that in assembling the tubes and connections it is necessary to spring the tubes to cause their end to receive the doweling parts. This results from inaccuracy in the production of the dowels or in their insertion in the connections. In any event the heating of the end portions of the tubes and the doweling connections relieves all strains so that when the frame is relieved of the clamping pressure in the machine there is no tendency for the various parts to spring out of their true positions.

Having thus temporarily and rigidly connected the several parts of the frame together in their true positions as determined by the machine, the frame is next removed

from the machine and the several connections are completed and made permanent by suitable brazing operations, such as by dipping the several connections into melted 5 brazing material after having first been prepared for such dipping by a previous dipping in a suitable acid.

After the completion of the several joints by the brazing process the frames are then 10 finished by the removal of the superfluous brazing material and the reaming and finishing of the several openings for the reception of the ball bearing parts and collars and then the frame is tested as to its 15 exact trueness or correctness in a machine which is similar to the machine in which the several parts were clamped and set as previously described.

While it would be possible to test the 20 frame thus completed in the machine as already described, I preferably provide a machine especially adapted for this testing operation, which machine I have illustrated in Figures 13, 14 and 15.

25 In describing the testing machine and its operation I will first describe the differences between the testing machine and the setting machine which are especially adapted to facilitate the testing operations.

30 Instead of the means for clamping the head by forcing it rearwardly I provide simple means for testing the alignment or position of the head 26. Instead of the threaded shaft 71 and head 70 for clamping 35 the rear part of the frame, I provide a similar head which is freely movable longitudinally of the machine for testing the positions of the rear slotted plates 31, and instead of the screw threaded clamping shaft 40 17 at the upper end of the standard 4 I provide a testing member which can be freely lifted up and down in a guide bracket for testing the position of the seat post connection.

45 In place of the cam shaft 37 I provide a straight shaft 97 longer than the head 26 and adapted to be centered therein by doweling caps 98 at the lower end and 99 at the upper end. The collar 98 is fixed on the shaft 97 and the collar 99 is removable therefrom and is adapted to be locked in position on the shaft and against the upper end of the head 25 by means of a locking pin 100 projecting laterally from the shaft 55 97 and an L-shaped slot 101 in the periphery of the collar 99. As best shown in Figure 15 the collar 98 is provided with a doweling projection 102 fitting within the lower end of the head 26 and the removable collar 99 is provided with a similar doweling projection 103 fitting within the upper end of the head 26 so that when the shaft is clamped in the head it stands in central position in relation to the head 26.

60 65 For centering the crank case 8 upon the

machine I provide exactly the same centering devices as used in the clamping machine, viz: the fixed doweling head 12 and the transversely movable doweling head 7, and in placing the bicycle frame in the testing machine I first clamp the crank case between these two heads by means of the screw threaded shaft 5 which carries the movable head 7.

Having thus clamped the crank case in 75 the machine it is now merely necessary to test the several extremities of the frame to find out whether they lie in their true and proper relation to the central vertical longitudinal plane of the testing machine. In 80 this process of testing I first test the seat post connection 10 and for this purpose instead of the screw threaded clamping shaft 17 I provide a shaft 104 which is mounted in vertical position with its axis lying accurately in the central longitudinal plane 85 of the machine and which is slideable up and down in a bearing 105 carried by the upper end of the standard 4 and provided on its lower end with a doweling pin 106 which 90 accurately fits in the seat post opening. For convenience in operation I provide a supporting pin 107 projecting laterally from the shaft 104 and I provide an upwardly projecting nozzle 108 on the bearing 105 95 upon which the projection 107 can rest with the lower end of the shaft 104 free of the bicycle frame and provided with a vertical slot 109 in which said projection 107 is received when it is desired to drop the shaft 100 with the dowel 106 in the seat post opening of the bicycle frame. At the time that the frame is first clamped in the testing machine the shaft 104 is raised and supported in raised position by the projection 107 resting 105 upon the top of the nozzle 108. After the frame has been clamped by clamping the crank case 8 tightly between the heads 7 and 12 then I test the upper part of the frame by means of the dowel 106 on the 110 lower end of the shaft 107, swinging the frame back and forth until the seat post connection is aligned transversely with the dowel and then if the dowel enters the seat post opening the frame is true, but if the 115 seat post opening stands to one side or the other the frame is sprung or forced side-wise until it stands accurately beneath the shaft 104 and so that the dowel 106 will freely drop into the seat post opening. 120 When this occurs it is known that the seat post connection lies accurately in the central longitudinal plane of the frame.

Having adjusted the frame so that the dowel 106 will drop freely into the seat post 125 opening I then proceed to test the accuracy of the position of the head 26. This is tested by means of the shaft 97 heretofore described and two testing heads 110 and 111 which are arranged to receive the upper 130

and lower ends respectively of the shaft 97. These heads are mounted upon longitudinally moving shafts 112 and 113 respectively carried in horizontal bearings provided in the standard 34. Each of these heads is U-shaped, as best shown in Figure 14, and adapted to be moved back and forth from and toward the frame to engage the ends of the shaft 97. These heads are at first in withdrawn positions, as shown in dotted lines. The U-shaped slots 114 are made wide enough to span the shaft 97 and in testing the accuracy of the position of the shaft 97 they are moved rearwardly. If they slide freely upon the ends of the shaft this indicates that the shaft and the head 26 lie accurately in the central longitudinal plane of the machine, but if they do not slide freely upon the ends of the shaft then the forward end of the bicycle frame is adjusted by forcing the head one way or the other, or twisting the frame until the heads 110 and 111 will slide freely upon the ends of the shaft 97 into the position shown in full lines in the drawing, at which time it is known that the head 26 lies accurately in the central longitudinal plane of the frame. The next point to test is the position and relation of the rear part of the bicycle frame. This is accomplished by means of a head 115 similar to the head 70 and slideable back and forth on a member 116 similar to the member 73. Instead of the screw threaded shaft 71 for forcing the head forward and back, I provide a guide shaft 117 which supports and guides the head 115 accurately. The head 115 is provided with a vertically movable block 118 similar to the block 68 and which carries a member similar to the member 61, simulating the rear axle and hub of the rear wheel of the bicycle, having shoulders 119 similar to the outer faces of the collar 62 on the member 61 for accurately spacing the rear slotted members 31 apart, and the member 61 is provided with diametrically extending projections similar to the projections 63 on the member 61 for entering and testing the positions of the slots in the members 31.

In testing the rear portions of the bicycle frame the head 115 is moved forward on the shaft 117, first to test the accuracy of the transverse positions of the slotted plates 31 and when these lie accurately against the shoulders 119, then the diametrical doweling projections are entered into the slots in the plates 31 to test the accuracy of their being parallel with each other. When the head 115 can be moved forwardly and the testing projections entered freely into the slots in the plates 31 with the inner sides of the plates 31 in contact with the shoulders 119, then it is determined that the rear forks are accurately spaced, uniformly from the longitudinal central plane of the frame and the

plates 31 with their slots for receiving the rear axle are at the same height and the slots in the two plates are exactly parallel one with the other.

The head 115 is provided with a forward projection 120 surrounding the shaft 117 and adapted to contact with the projection 81 when the block 115 is at the extreme forward limit of its movement, thus testing the accuracy of the spacing of the crank case 75 8 from the position of the axle of the rear wheel, whereby it is known that a certain length of chain can be used and will accurately fit upon the gear wheel and sprocket of the machine when assembled and bring 80 the adjustment of the rear axle within the length of the slots in the plates 31 in the removal or addition of a link, as the chain needs adjustment in the use of the machine.

For testing the points 90 on the rear forks 85 as to their exact spacing from the center plane of the frame, I provide two testing forks 121 mounted in the testing machine and similar to the U-shaped members 84 on the clamping machine. These testing forks 121 are each provided with a transversely arranged caliper rod 122 at its free end, the ends of the rod 122 adapted to just pass the inner sides of the adjacent rear fork sides when the testing forks are 95 swung up and down. The ends of the rods 122 are set equidistant from the center plane of the frame and the rods are the proper length to test the spacing of the rear forks.

Having thus tested and adjusted the frame 100 to lie with its longitudinal vertical plane accurately in the longitudinal vertical plane of the machine the frame is then removed from the machine and is ready to be finished by the usual enameling process, and it is 105 known that when the frame is assembled with the other parts of the bicycle to form the complete bicycle every part and portion thereof will be in proper alignment and relative position and will not need to be adjusted in such assembling.

As many modifications of my invention will readily suggest themselves to one skilled in the art I do not limit nor confine my invention to the several specific steps or sequence of steps of the several specific constructions herein described and shown.

I claim:

1. The herein described method of building tubular frames which consists in clamping one part of the frame provided with means for doweling tubular parts thereon in a fixed position, setting the remaining connections in positions relative to said fixed connection, with tubular connecting 120 parts arranged between said connections, then forcing said remaining connections towards the fixed connection to tightly clamp the intervening tubes and while the several parts of the frame are thus clamped, rigidly 125 130 135 140 145 150 155 160 165 170 175 180

and permanently securing the several connections to the several tubes so that when the connections are relieved of pressure the several parts will remain rigid in their true 5 fixed positions.

2. The herein described method of building tubular frames which are symmetrically arranged in reference to a longitudinal central plane, which consists in clamping one 10 part of the frame provided with means for doweling tubular parts thereon in a fixed position with its transverse center plane in said longitudinal central plane, setting the remaining connections in their several 15 positions relative to said fixed connection with tubular parts doweled upon and arranged between said several connections, then forcing said remaining connections toward the fixed connection to tightly clamp the intermediate tubes and holding them centrally 20 relatively to said longitudinal central plane, and while the several parts of the frame are thus clamped, rigidly and permanently securing the several connections to the several 25 tubes so that when the connections are relieved of pressure the several parts will remain rigid in their true relative positions.

3. The herein described method of building tubular frames consisting of tubular 30 parts joined to a hollow connecting part, which consists in loosely doweling the tubular parts upon the connection, fixing the opposite ends of said tubular parts in their true relative positions, and forcing the connection in the general direction of the fixed 35 ends of the tubular parts to close the joints between the tubular parts and the hollow connection, and while the parts are thus held, rigidly welding the hollow connection 40 to the tubular parts.

4. The herein described method of connecting a hollow connecting member to two tubular parts extending from one side thereof which consists in providing the hollow 45 member with connecting nozzles, placing doweling tubes in said nozzles having flanged projections extending within the hollow connection, placing tubular members on said doweling tubes, fixing the free ends 50 of the tubular parts in their true relative positions, then applying pressure to the flanged ends of the doweling tubes and forcing said flanges against the inner surface 55 of the hollow connections and the hollow connection in the general direction of the fixed ends of the tubular parts to close the joints between the tubular parts and the nozzles, and while the parts are thus clamped producing metalized connections 60 between the nozzle and the tubular parts.

5. The herein described method of building a tubular frame which consists of a substantially central connection and end connections and tubular parts joining the connections, which method consists in loosely 65

assembling the several parts of the frame, clamping the central connections rigidly in desired positions relatively to a central longitudinal plane, then forcing the several other connections towards the said central 70 connection with the several tubular parts interposed and while forcing said several connections toward the central connection, holding all of said connections in their desired positions relatively to said central longitudinal plane of the frame to be produced, and when the several other connections have been forced toward the central connection to tightly clamp the tubes, producing molecular connection between the tubes and the 75 several connections for rigidly retaining the parts in their several related positions.

6. The herein described method of building a tubular bicycle frame consisting of a hollow crank case, a hollow head, a hollow 80 seat post connection, slotted rear wheel connections and tubular members connecting the several connections, which method consists in clamping the crank case with its transverse center plane in a given plane, 85 setting the head in said given plane with the tube arranged between the head and the crank case, setting the seat post connection in said plane with a tube arranged between the crank case and the seat post connection, 90 and another tube arranged between the seat post connection and the head, setting slotted plates for the rear wheel axle parallel to each other and at equal distances from said given plane and interposing tubular 95 connections between said slotted plates and the crank case, and between said slotted plates and the seat post connection, holding the head connection and the seat post connection in said central longitudinal plane and 100 the slotted connections at the rear in the said positions relative to said plane and forcing all of said connections toward said fixed crank case and forcing the head and said slotted connection toward the seat post 105 connection to clamp all of the tubes endwise between the several connections and while thus clamped rigidly securing said tubes at their ends to the several connections by welding.

7. The herein described method of centering and spacing the rear, side frames of a bicycle frame in the manufacture thereof which consists in holding the crank case connection and the seat post connection in 110 fixed positions relatively to each other and with their transverse center planes in a given plane, arranging the slotted connections for the rear wheel axle at equal distances from said plane and parallel to each 115 other and with suitable tubes joining said slotted connections to the crank case and seat post connections, then applying pressure to said slotted connections to force them 120 forwardly toward the crank case and toward 125 the seat post connection.

- the seat post connection to firmly clamp the said tubes endwise between the connections, arranging a separator between the two upper tubes at the point just beyond that which will be occupied by the rear wheel tire and a similar spacer between the lower bars and forcing said tubular connections between the upper and lower bars, then permanently connecting all of the side tubes to the rear slotted connections, the lower tubes to the crank case, the upper tubes to the seat post connections and the hollow braces to the upper and lower tubes respectively.
15. 8. In a machine of the kind described, means for holding the rear ends of the upper and lower bars of the forward end of a bicycle frame in proper relative position, and cam means for forcing the head connection toward said rear ends to clamp said head upon said tubes.
9. A machine for building bicycle frames having a central longitudinal plane, means for clamping the crank case with its transverse center plane in said central plane of the machine, means for holding the seat post connection with its center in the said central plane, means for holding the head of the bicycle frame centrally in relation to said center plane, means for forcing the seat post connection toward the crank case, means for forcing the head connection in the general direction of the seat post and the crank case to cause the tubes of the bicycle frame to be tightly clamped endwise, while the several connections are retained in said central plane and to be retained in such position while being permanently joined as by welding.
40. 10. A machine for building bicycle frames having means for rigidly clamping the crank connection in a given position with its transverse center plane in the longitudinal central plane of the machine, a head mounted on the machine carrying a horizontal shaft having end shoulders equi-distant from said central plane and adapted to receive and space the rear slotted connections of the bicycle frame, parallel projections on the two shoulders for aligning the slots of said rear slotted connections, means for clamping the connections against said shoulders, means for positioning a seat post connection above the crank connection and centered on said central plane, and means for forcing the said head toward the crank case to tightly bind tubular members joining the several connections.
11. A machine for building bicycle frames having means for rigidly clamping the crank connection in a given position with its transverse center plane in the longitudinal central plane of the machine, a head mounted on the machine carrying a horizontal shaft having end shoulders equi-distant from said central plane and adapted to receive and
- space the rear slotted connections of the bicycle frame, parallel projections on the two shoulders for aligning the slots of the rear slotted connections, means for clamping the connections against said shoulders, means for positioning a seat post connection above the crank connection and centered on said central plane, means for forcing the said head toward the crank case to tightly bind tubular members between the connections and to hold them in such condition, and means carried by the head for centering the upper and lower parts of said rear frame between their ends.
12. A machine for building bicycle frames having means for rigidly clamping the crank connection in a given position with its transverse center plane in the longitudinal central plane of the machine, a head mounted in the machine carrying a horizontal shaft having end shoulders equi-distant from said central plane and adapted to receive and space the rear slotted connections of the bicycle frame, parallel projections on the two shoulders for aligning the slots of said rear connections, means for clamping the connections against said shoulders, means for positioning a seat post connection above the crank connection and centered on said central plane, means for forcing the said head toward the crank case to tightly bind tubular members between the connections, and means carried by the head for centering the upper and lower parts of said rear frame between their ends.
13. A machine for building bicycle frames having means for rigidly clamping the crank case in a given position with its transverse center plane in the longitudinal central plane of the machine, a head mounted on the machine carrying a horizontal shaft having end shoulders equi-distant from said central plane and adapted to receive and space the rear slotted connections of the bicycle frame, parallel projections on the two shoulders for aligning the slots of the rear slotted connections, means for clamping the connections against said shoulders, means for positioning a seat post connection above the crank connection and centered on said central plane, means for forcing the said head toward the crank case to tightly bind tubular members between the connections, and means carried by the head for centering the upper and lower parts of said rear frame between their ends.
14. A machine for building bicycle frames having means for rigidly clamping the crank case in a given position with its trans-

- verse center plane in the longitudinal central plane of the machine, a head mounted on the machine carrying a horizontal shaft having end shoulders equi-distant from said central plane and adapted to receive and space the rear slotted connections of the bicycle frame, parallel projections on the two shoulders for aligning the slots of the said rear connections, means for clamping 10 the connections against said shoulders, means for positioning a seat post connection above the crank case and centered on said central plane, means for forcing the said head toward the crank case to tightly bind 15 the tubular members between the connections, and a stop for limiting the forward movement of the head to a determined position which shall correctly space the crank connection from the slotted connections. 20 15. The herein described method of building tubular frames which consists in clamping tubular parts between tubular connections with doweling members joining said parts, then permanently and rigidly joining 25 the ends of the tubular members to the connections and dowels by means of heat and thereby relieving the strains incident to the clamping operation. 16. The herein described method of building tubular frames which consists in compressively clamping tubular parts between hollow connections with doweling members joining said parts, then spot welding the 30 ends of the tubes to the connections to temporarily rigidly hold the several parts in 35 their relative relations, then relieving the parts of compression and brazing the several joints. 17. The herein described method of producing rigid tubular structures consisting 40 of tubular members joined to tubular connectors by tubular dowels having flanged heads, which method consists in placing the tubular dowels with their flanges inside of 45 the tubular connectors, placing the ends of the tubular members on the projecting ends of the dowels, then forcing the tubular connections toward each other to place the tubular members under compression by pressure applied to the flanged ends of the dowels and while the parts are thus held 50 metallically and rigidly joining the tubular parts to the connections and dowels. 18. In a machine for building the rear portion of bicycle frames, means for rigidly 55 clamping the crank case in a fixed position with its transverse center plane in the longitudinal central plane of the machine, means above the crank case for positioning a seat post connection with its vertical central plane in the central plane of the machine and for compressively clamping the tubular member between the crank shaft and the 60 seat post connection, a longitudinally movable head mounted on the machine carrying 65 a shaft arranged perpendicularly to the central plane of the machine and having end shoulders equidistant from the central plane and adapted to receive and space the rear slotted connections of the frame, tubular 70 members between the rear slotted connections and the crank case and seat post connection the transverse shaft being freely movable bodily up and down to accommodate itself to the relative length of the connecting tubular members so that when the head is moved to place the tubular members under compression the compression will be 75 equalized upon the upper and lower tubes. 19. In a machine for building tubular 80 frames such as bicycle or similar frames having a part comprising two side members joined together at one end and spaced apart at their opposite ends to receive a wheel between them, fixed means for retaining the joined ends symmetrically in reference to the central plane of the machine, a movable head adapted to receive and symmetrically position the free ends of the members, and a strut pivotally mounted on 85 the head to swing between the members and adapted to be set a transverse brace between the two members for symmetrically positioning the members between their ends in reference to the central plane as the head is 90 moved to produce compression upon said members. 20. In a machine for building tubular 95 frames such as bicycle or similar frames having parts symmetrically arranged in reference to a central plane, and comprising a crank case, a seat post connection, a tube joining said parts, symmetrically formed rear forks extending from the crank case and seat post connections and joined together at their rear ends by rear wheel supporting plates, means on the machine for setting and holding the crank case with its transverse central place in the central plane 100 of the machine, means for forcing the seat 105 post connection toward the crank case, a head longitudinally movable on the machine and adapted to symmetrically position the rear wheel supporting plates, struts pivoted to the head and adapted to swing between the lower and upper forks of the cycle 110 frame, and adapted to set transfer braces between same when the head is moved forward to set the tubular side members upon the crank case and seat post connections. 115 21. In a machine of the kind described, means for rigidly holding the crank case connection of a cycle frame, a head adapted to receive the free ends of the rear fork of the frame and longitudinally movable on the machine for forcing the tubular members of the rear fork toward the crank case 120 connection, a member mounted at one end on said head adapted to extend out along 125 said support and to set the side members 130

transversely equal distances from the central plane at a point between their ends.

22. In a machine in the kind described, means for rigidly holding the crank case connection of a cycle frame, a head adapted to receive the free ends of the rear fork of the frame and longitudinally movable on the machine for pushing the tubular members of the fork toward the crank connection, a member pivotally mounted at one end on said head, its free end portion adapt-

ed to be engaged with sides of the fork between their ends at points adjacent to the periphery of the wheel to be carried thereby and adapted to set said sides equally distant 15 from the central plane of the machine at said points.

Signed at Chicago, Illinois, this 17th day of April, 1920.

AUGUST E. MEISELBAECH
